STEEL CRIBBING

Elmer S. Utzler, Pittsburgh, and Max A. Schlienger, Bellevue, Pa., assignors to Pressed Steel Car Company, Inc., Pittsburgh, Pa., a corporation of Pennsylvania

Application July 19, 1938, Serial No. 220,032

15 Claims. (Cl. 61—47)

The present invention pertains to steel cribbing used in erecting retaining walls, either with or without a superposed loading in addition to the material filling in the spaces behind the face of the retaining wall.

Among the objects of the present invention are the provision of individual members forming the cribbing, which members are light in weight so as to be readily handled, have a low cost of manufacture, are quickly and cheaply assembled, and of a design to develop greater strength for a given weight of the material used.

In addition to the mechanical features of the cribbing structure the members comprising the outer wall thereof are designed to provide an exposed closed face therefor of improved appearance which may be obtained in a cribbing structure having the face thereof in one plane or provided with offsets or corners in the front wall. These and other objects will be made apparent as the description proceeds.

While we are aware that cribbing structures of the general type disclosed in the present invention are not new in that cribbing structures are well known to the art, first in the form of wood, later in the form of concrete, and more recently formed of steel, all of the cribbing structures heretofore known utilized the end portions only of the header to carry compressive as well as tension loading by interposing the ends of the header between two stretchers of the cribbing wall. This resulted in the formation of open spaces between the vertically disposed rows of stretchers forming the front wall of the cribbing, and in cases where the cribbing was used as a retaining wall, resulted in not only an unsightly appearance, but also permitted the earth, rock, or other filling materials to fall through these openings and be deposited at the foot of the structure. Many different attempts have been made to close these openings with varying degrees of success.

In the present invention it is not only possible to provide a closed front wall for the cribbing structure but a closed wall which readily lends itself to various embossments which not only contribute greatly to the strength of the structure but may be of forms simulating brick or stone and which may be painted with any desired materials for enhancing the appearance or increasing the corrosive resisting qualities of the metal.

Most of the cribbing structures of the type with which this invention is concerned are designed as permanent structures, that is, to remain in place after being once erected. However,

there are times when it has been desired to erect only temporary structures and the present invention lends itself readily to quick and easy assembly and dis-assembly by reason of certain features hereinafter more fully described, and by the absence of loose fastening means between the various members comprising these structures.

The various members comprising the present invention are unique in form and distinguish from other similar structure known to the prior art by reason of the design thereof which not only makes all portions of the members readily accessible for application of a protective medium whether it be galvanizing, painting, or any other medium used for a similar purpose, but in addition provides flexibility of assembly in various heights, lengths, and contours of the wall.

Referring now to the drawings: Fig. 1 shows in perspective a portion of a cribbing wall embodying the invention. Fig. 2 shows a typical cross section through the wall such as on line 2—2 of Fig. 1 and illustrates the manner of assembling and connecting the various component members to form the wall shown in Fig. 1. Fig. 3 shows in enlarged detail typical sections through superposed stretcher members of Fig. 2. Fig. 3a shows an end elevation of the stretcher members. Fig. 4 shows a section taken on line 4—4 of Fig. 2 to illustrate the cross section of the header member connecting spaced stretcher members. Figs. 5 and 6 show enlarged typical elevations of the front and rear faces of superposed stretcher members, the vertical mid portions of said figures showing abutting end portions of the members and the upper and lower portions of the figures showing the longitudinal mid portions of adjacent stretcher beams. Figs. 7 and 8 show in enlarged detail a portion of the front face and top flange, respectively, of the stretcher members. Fig. 9 shows in elevation a portion of the wall taken on lines 9—9 of Fig. 1, illustrating the assembly of stretcher and header members, and the three types of fillers used. Figs. 10 and 11 show plan views of the stretcher members at corners or offsets in the face of the cribbing structure. Fig. 12 shows in enlarged detail the angle portion of the stretcher member of Fig. 10. Figs. 13 to 16, inclusive, show sections taken on corresponding lines of Figs. 10, 11 and 12. Fig. 17 shows the arrangement of stretcher and header members at an offset in the face of the cribbing structure. Fig. 18 shows in elevation a portion of the face of the wall illustrating arrangement of stretcher beams shown in Figs. 7 and 11. Figs. 19 and 20 are typical sections taken on lines 19

and 20 of Fig. 17. Fig. 21 shows the arrangement of stretcher and header members at an end of the cribbing structure. Fig. 22 shows a section taken on lines 22-22 of Fig. 21. Figs. 23 to 25, inclusive, show typical sections taken on corresponding lines on Fig. 22. Fig. 26 shows a portion of the face of the wall to illustrate the arrangement of stretcher and header members providing drainage openings at the base of the cribbing structure. Fig. 27 shows a section taken on lines 27-27 of Fig. 26 for the same purpose. Fig. 28 shows in elevation the assembly of the capping members with the stretcher members at the top of the wall structure. Fig. 29 is a section through the capping and stretcher members taken on lines 29-29 of Fig. 28.

Referring now in detail to the drawings where like reference characters refer to like parts, the cribbing structure comprises a front wall formed of a plurality of staggered rows of superposed stretcher members 1, a rear wall comprising a plurality of rows of vertically spaced stretcher members 1, with fillers 2 between the vertically spaced rows of said latter stretcher members, and the stretcher members of the front and rear walls connected by header members 3. As illustrated in Fig. 1 of the drawings, where an offset or corner is formed in the structure, the stretcher members 1 are displaced by stretcher members 4 forming the outside corner and stretcher members 5 forming the inside corner of the front wall of the cribbing structure. It being understood that where sufficient space or length of wall permits, the usual stretcher 1 is used between the stretcher members 4 and 5 to complete the wall as illustrated in Figs. 1 and 17 of the drawings.

Following the usual practice originating in wood and concrete cribbing structures, where the structures are of considerable height the header members 3 are of different lengths. As an example, in the wall illustrated in Fig. 1, the lower header members 3 are 8 ft. in length; the intermediate header members 3^a, 6 ft. in length; and the top header members 3^b, 4 ft. in length. Where the height of the wall necessitates additional anchorage, it is sometimes deemed advisable to place one or more lower rows of stretchers 1 rearwardly of the two previously recited stretcher members, as illustrated in Figs. 1 and 2, which additional rows of stretcher members are connected in the usual manner by header members 3.

At the top of the wall when appearance is important, a capping member 6 is sometimes used and as the cribbing structure or retaining wall is not always of the same vertical height throughout its length the capping members 6 may present a stepped appearance as illustrated in Fig. 1 of the drawings.

Referring now to Figs. 2, 3, 3^a, 8 and 9 of the drawings, the stretcher members 1 are preferably of pressed metal substantially channel shape in cross section and are assembled in the front wall of the structure as superposed staggered rows of uniformly loaded beam members fixed at both ends.

In the rear wall of the structure the stretcher members may be arranged as in the front wall, or if desired, the rows of stretcher members may be vertically spaced with filler members supporting adjacent ends of abutting stretcher members in each row. These stretchers in either case are arranged with the flanges thereof directed toward the flanges of the stretchers at the opposite ends of the connecting header.

In either of the above arrangements the stretcher members comprising opposing walls of the structure are connected by header members which act merely as tension members.

Referring in detail to the stretcher members 1, each comprises a substantially vertical web 7, top flange 8, and bottom flange 9 integrally formed. The bottom flange 9 is wider than the top flange 8 and provided with a depending flange 10 extending longitudinally of the stretcher 1 and spaced outwardly of a vertical plane through the outer free end of the top flange 8. The top flange has a plurality of apertures 15 therein spaced longitudinally of the member 1. The bottom flange 9 has a plurality of apertures 16 registering with the apertures in the top flange and provided with depending annular flanges 16^a, the outside diameter of the flanges 16^a being less than the diameter of the apertures 15 so that the flanges 16^a of one stretcher member will engage within the apertures 15 of an adjacent stretcher member when the stretcher members 1 are assembled in superposed relation. As it is sometimes desirable to arrange the superposed rows of stretcher members in staggered relation so that abutting ends of stretcher members in one row meet adjacent the center of a stretcher member in the adjacent row, it has been found desirable to space the apertures 15 and 16 along the flanges 8 and 9 of the stretcher member 1 equally distant from each end of the stretcher and about the vertical centerline through the stretcher.

In retaining walls formed of stretcher members assembled in the manner described supra the pressure on the wall from the filling medium behind the walls varies with the moisture content and nature of such filling medium. In any condition other than a fluid state, the pressure from the filling medium is not along horizontal lines but inclined downwardly so that there is both a vertical and horizontal component of the force exerted upon the stretcher members, the vertical component being least when the filling medium approaches a fluid state.

Because of vertical forces exerted on the stretcher members it is necessary to provide certain vertical reinforcements. These are provided by the vertical embossments 14 in the web 7 of the stretchers and by the members 13 disposed between the flanges 8 and 9 and preferably in spaced relation to the web 7 of the stretcher members. Due to the aforesaid staggered arrangement of the rows of stretcher members it is preferable to dispose the vertical reinforcing members 13 adjacent the apertures 15 and 16 in the flanges 8 and 9 as illustrated in Figs. 7 and 8 of the drawings. Where required additional members 13^a may be used as shown on Fig. 8.

For purposes of improving the appearance of the face of the wall formed of these stretcher members in the manner described, the stretcher web 7 of the member is preferably embossed outwardly, the major portion of the embossment being vertically disposed and joining the flanges by inwardly inclined portions as illustrated in Figs. 3 and 8 of the drawings. To further improve the outward appearance of the face of the wall it is preferable to space the vertical embossments 14 in the web 7 of the stretcher so as to simulate the joints between cut stone.

As previously stated, the header members 3, connecting opposing stretcher members in the opposing walls of a structure of the character described, function merely as tension members

so that the means connecting the stretcher members 1 and header members 3 are in shear only. At each end of the stretcher member, as illustrated in Fig. 3^a, are preferably vertically disposed flanges 11 formed by turning a portion of the vertical web 7 of the stretcher rearwardly and between the flanges 8 and 9. The horizontal edges of the flange 11 may be integrally formed with flanges 8 and 9 as in Figs. 3, 5 and 6 but are preferably in spaced relation to flanges 8 and 9 since they are not needed to contribute to the vertical reinforcement of the stretcher member. However, as the body of the stretcher member is built of light plate, usually $\frac{1}{8}$ " or less, these flanges may become distorted in handling or shipping and for that reason we prefer to tack weld the upper outer corner of the flange 11 to the flange 8 as at 37. In order to secure the header member 3 to this flange, one or more apertures 38 are formed in the flange 11 to receive the flanges 39^a of the apertures 39 placed in the header member 3. As it is sometimes desirable to place a header intermediate the ends of the stretcher, a member 12 apertured in the same manner as member 11 may be vertically disposed at substantially the vertical medial line through the stretcher member 1 and connected with either the flanges 8 and 9 or the web 7, or both.

From the foregoing description of the construction of the stretcher members, and particularly the disposition of the flanges thereof, it will be apparent that the flange 9 with its depending portion 10 combined with the web 7 produces a substantially Z-shape resisting both horizontal and vertical deflection of the stretcher. Thus, in the front wall of the structure where the stretchers are in superposed relation and in the rear wall where the stretchers are in vertically spaced relation the said Z-shape and vertical members 13 carry substantially all the vertical loading placed on the stretchers. As shown in Fig. 9 the members 13 combine with the stretcher member flanges 8 and 9 to form a continuous beam extending substantially from top to bottom of the wall. The filler 2 in the back face of the wall acts as a short stretcher to transmit the load to the next lower stretcher.

As illustrated in Figs. 2 and 4 of the drawings, the header members 3 are preferably formed of pressed metal, channel shaped in cross section, comprising a vertical web 17 having integrally formed top and bottom flanges 18. To further increase the strength thereof the header members 3 are preferably made pan-shaped having end portions 19. Adjacent each end of the header 3 in the vertical web 17 are vertically spaced apertures 39 having annular flanges 39^a adapted to register with the apertures 38 in the header connection members 11 and 12 of the stretcher member 1. Some of the header members 3 have suitable apertures 26 spaced longitudinally of the member in the web 17 thereof and members 22 disposed between the flanges 18 at said apertures for a purpose hereinafter described.

The filler members are indicated as 2, 2^a, and 2^b on Fig. 9 and may be described as filler, half filler, and step-back filler, respectively. The filler 2 is preferably the same in cross section as a cross section through the stretcher 1 with the flange 10 preferably omitted and is functionally a short stretcher. Intermediate the ends of the filler is a vertical member 12 preferably such as used in the stretcher member 1 and functioning as such when

required. The ends of the filler member 2 are preferably closed and at each end are vertical reinforcements 13 such as used in the stretcher 1. On opposite sides of the vertical member 12, and 5 of the same spacing as in the stretcher members 1, are the apertures 40 in the top flange and the apertures 41 with flanges 41^a in the bottom flange of the filler the same as in the stretcher 1. This 10 filler 2 substitutes for a stretcher member 1 where vertically spaced rows of stretcher members form the wall.

The half filler 2^a illustrated in Fig. 9 is the same in cross section as the filler 2, having one reinforcement member 13 and one header connection member 12. It will be observed that the 15 filler 2^a is substantially one-half the overall length of the filler 2 and has but one aperture in each of the top and bottom flanges, similar in all respects to those in the top and bottom flanges of the filler 2. The half filler 2^a is used at the ends of the wall or row of stretcher members.

The step-back filler 2^b as illustrated in Fig. 9 is channel-shaped in cross section having the web of the channel of greater vertical height than the vertical height of the fillers 2 and 2^a. Upon reference to Fig. 9 of the drawings it will be observed that the filler 2^b extends from beneath the flange 9 of the stretcher member to the next adjacent lower header member, the top flange of the step-back filler being of greater length than the bottom flange and having two apertures 42 therein spaced the same distance on either side of the central vertical reinforcing member 13^b as in the filler 2, and the bottom flange of the step-back filler 2^b having no aperture therein, merely resting upon the adjacent header 3. The step-back filler 2^c is of the same vertical height as the step-back filler 2^b and substantially one-half the width thereof. As illustrated in Figs. 2 and 9, the 25 step-back fillers 2^b and 2^c respectively are used only at the points where the header members are of different length and the stretcher members are disposed above a header member so that the step-back filler has a top flange in engagement with 30 the abutting stretcher members and its bottom flange resting on the adjacent header member, the step-back filler 2^c being a special filler and used only at construction joints so that its top flange engages but one stretcher member and its bottom flange engaging the adjacent lower header member.

Referring now to the stretcher members 4 and 5 forming the corner or offset in the front wall of the structure and particularly Figs. 1, and 10 to 16 inclusive, the stretcher member 4 being known as an outside corner stretcher and the stretcher member 5 being known as an inside corner stretcher. These stretcher members are shown angular in form having one leg of the angle longer than the other, and are made right and left hand when the stretcher members are assembled in staggered relation as shown in Fig. 1 of the drawings, that is, the abutting edges of two adjacent stretchers in the same row are disposed intermediate the ends of the adjacent stretcher in the next adjacent row. Thus, by making the stretcher 5 right and left hand, insofar as the length of the legs is concerned this staggered arrangement can be maintained on the angularly disposed faces of the wall as well as on the front face thereof.

The stretcher member 4 is of the same contour in cross section as the stretcher member 1 and has the longer leg thereof of a length greater than one-half the length of a full-sized stretcher

1. The angular form of the stretcher is preferably produced by cutting a V-shaped section out of the top and bottom flanges thereof and bending the web rearwardly till the flanges on one side of the V-shaped cut meets the flanges on the other side and welding the flanges together. It is also preferable to locate one of the vertical reinforcing members 13 at this point, as illustrated in Fig. 11 of the drawings.

The inside corner stretcher 5 is formed by cutting the flanges 8 and 9 of the stretcher and bending the web 7 of the stretcher to form an inside corner. The opening formed by the bending of the flanges being preferably filled in by oppositely disposed offset plates 36 secured to the inner faces of the flanges 8 and 9 and these plates are vertically reinforced by the usual reinforcing member 13 as illustrated in Figs. 10, 12 and 14 of the drawings, thereby providing full bearing surfaces on the top and bottom flanges of the corner stretchers at the offsets therein. As previously stated, the stretchers 4 and 5 are in all respects similar to the stretchers 1 except for modifications just described.

Referring now to Figs. 21 to 25 inclusive wherein is disclosed the arrangement and details of the header members at a construction joint. When erecting retaining walls of cribbing of the type described supra, and particularly where considerable length of wall is being erected, it is oftentimes desirable to fill in behind portions of the partially erected wall before erecting the remaining portions of the wall. In such cases the filling medium being disposed on opposite sides of all but the end row of header members 3 prevents lateral distortion of the header members. At the end of the wall, however, the header members 3 will have but one side in engagement with the filling medium and in order to stiffen these header members we have provided a tie 20 having re-entrant flanges 21 at opposite ends thereof. These tie members 20 extend between the end headers 3 and the next adjacent headers 3 at the end of the wall with the flanges 21 embracing vertical stiffening members 22 in the headers 3 as shown in Figs. 21 to 24 inclusive of the drawings, thereby preventing lateral deflection of the end members 3.

In some cases where it is not desirable to continue the face of the wall across the ends of the wall as shown in the off-sets of the wall in Fig. 1 of the drawings, the header members 3 are left exposed at the end of the wall. As shown in Figs. 2 and 22 of the drawings these header members at the ends of the wall are spaced apart and the filling medium behind the face of the wall would escape through these spaces unless confined. For the purpose of confining the filling medium, filler headers 3c are inserted. These filler headers are substantially the same in construction as the headers 3 but are used only at the ends of the wall and thus, there being no similar filler headers 3c between the next adjacent vertical row of headers inwardly from the end of the wall, tie bars 20 cannot be used to prevent deflection of the headers outwardly of the wall under pressure from the filling medium. For this reason another means is provided for preventing deflection of the filler headers 3c which means comprises an angular member of sufficient length to overlap the top and bottom flanges respectively of the adjacent headers below and above the filler header as shown in Figs. 22 and 23 of the drawings. This member 23 is secured in place by means of the member 24 riveted thereto and having its free

edge provided with a flange engaging the stiffener 22 of the filler header 3c as illustrated in Figs. 22 and 25 of the drawings, the member 24 being fastened to the stiffener 22 by means of the bolt 25.

Referring now to Figs. 26 and 27 of the drawings, it is necessary in a retaining wall having a closed face as disclosed in the drawings to provide some means for drainage in order to reduce hydrostatic pressure behind the face of the wall. For this purpose it is desirable to omit stretcher members at spaced intervals Y in several of the lower courses of stretcher members forming the face of the wall and adjacent the base of the wall. In cases where the courses of stretcher members are in staggered relation as disclosed in the drawings, the joints between adjacent stretcher members in the courses of stretcher members above and below the drainage opening would be unsupported and for this purpose a filler member 27 is provided as illustrated in Fig. 26 of the drawings. This filler member is in form a miniature stretcher member having apertures 15 and 16 in the top and bottom flanges thereof spaced as in the stretcher member 1 so as to match up with the adjacent courses of stretcher members. It will be observed that a filler 2 can advantageously be used as a substitute for member 27.

At the top of the wall in order to finish off same, it is oftentimes desirable to provide a cap 6, one form of which is illustrated in Figs. 28 and 29 of the drawings, comprising a hollow substantially U-shaped member having a web 28, top and bottom flanges 29 and 30, the top flange 29 preferably being provided with a depending flange 31 at the rear edge thereof. A vertically disposed reinforcing member 32 is preferably disposed between the top and bottom flanges and secured thereto, preferably by welding. In the bottom flanges 30 of the member 6 are suitably spaced apertures matching with similar apertures placed in the top flange of the stretcher members 1 through which are inserted suitable fastening means such as the bolts 33 securing the cap 6 to the top course of stretcher members.

Having thus described the invention what we claim as new and desire to secure by Letters Patent is:

50. 1. In a retaining wall, the combination of superposed rows of abutting channel shaped stretcher members having header connection flanges and top and bottom flanges extending rearwardly from the face of the wall, means on the top and bottom flanges of each stretcher member registering with complementary means on the flanges of adjacent stretcher members for securing the members against lateral displacement, vertically spaced rows of channel shaped stretcher members having abutting header connection flanges and disposed rearwardly of said superposed stretcher members, the flanges of said second-named stretcher members being directed towards said first-named stretcher members, substantially channel shaped filler members disposed between the spaced rows of said second-named stretcher members, at least one flange of the filler member engaging adjacent ends of the flanges of two abutting second-named stretcher members, similarly registering complementary means on said filler member flanges and the adjacent second-named stretcher member flanges engaging to resist lateral displacement, and channel shaped header members connecting the opposite first-named and second-named stretcher mem-

bers, said header members being disposed at the ends of the first-named and second-named stretcher members and between the flanges of the first-named and second-named stretcher members, the end portions of said header members and the header connection flanges of said stretcher members being provided with similar registering complementary engaging means to prevent lateral displacement of the connected stretcher and header members.

2. In a retaining wall in combination, a plurality of superposed rows of stretcher members each including a vertical web having rearwardly disposed horizontal flanges at opposite vertically spaced edges thereof, means securing together the horizontal flanges of contiguous stretcher members, header members each having one end disposed between said flanges in spaced relation to the upper horizontal flanges thereof and secured to alternate rows of said superposed stretcher members, vertically spaced rows of similar stretcher members oppositely disposed to said first-named stretcher members and having flanges overlying the other of the ends of said header members, filler members between said rows of second-named stretcher members, and means securing together said header and the first-named and second-named stretcher members and said filler and the second-named stretcher members.

3. In a cribbing structure including front and rear walls, the combination of superposed rows of stretcher members forming the said walls, each stretcher member comprising a vertical web having vertically spaced horizontally disposed flanges, horizontally disposed header members spaced longitudinally of the walls between the walls and engaging between the flanges of alternate rows of the stretcher members, suitable connecting members on said stretcher members connected to the ends of said header members, said header members being of less vertical height than the spacing between said stretcher member flanges, and means securing said superposed stretcher members together and said header members between said stretcher member flanges.

4. In a cribbing structure of the character described, with header members extending from alternate rows of stretcher members, a filler header member between adjacent vertically spaced header members and comprising a vertical web having rearwardly extending top and bottom flanges, a member disposed across said web and connecting the said flanges, a member disposed across said flanges and extending beyond the horizontal plane of said flanges for engagement with adjacent header members above and below said filler member, and means connecting the member between the filler member flanges and the member extending across filler member flanges.

5. In a cribbing structure having a front face, a portion of which is disposed at an angle to other portions of the front face to form a corner or offset in said face, the combination of superposed rows of substantially channel shaped stretcher members forming the front face of the structure, means connecting said stretcher members preventing relative lateral displacement, header members spaced longitudinally of said face between the flanges of alternate rows of said stretcher members and secured thereto, said offset or corner in the face of the cribbing structure being formed by stretcher members having portions of the length thereof disposed at an

angle to the remaining portions of the length of the stretcher member with header members engaging between the flanges of alternate rows of the angularly disposed portions of the stretcher members, said latter-named header members also extending at an angle and between the first-named header members so that no stretcher member offset or cornered in the wall shall have two header members connected therewith and disposed at an angle to each other.

6. In a cribbing structure of the character described a stretcher beam comprising a vertical web extending longitudinally of the beam, top and bottom flanges disposed rearwardly of said web, connected therewith, and extending substantially the length thereof, vertically disposed end flanges on said web disposed between said top and bottom flanges, a vertically disposed member mid-way the ends of the beam and connected to said web between the top and bottom flanges, and vertical reinforcing members for said beam spaced equi-distant on opposite sides of said vertically disposed member and the same distance inwardly from each end flange of the beam.

7. In a cribbing structure of the character described a stretcher beam comprising a vertical web extending longitudinally of the beam, a flange disposed rearwardly of the upper edge of said web, connected therewith and extending substantially the length thereof, a flange disposed rearwardly of the bottom edge of said web, connected therewith and extending substantially the length thereof, the free edge of said bottom flange having a depending portion disposed outwardly of the vertical plane of the free edge of the upper flange of said beam, a vertically disposed member connecting said web and upper and lower flanges and disposed intermediate the ends of the beam, end flanges on said web disposed between said top and bottom flanges of said beam and vertical reinforcing members disposed equi-distant on opposite sides of said intermediate member and a similar distance inwardly from each end flange, said latter reinforcing members being connected to said upper and lower flanges.

8. In a metal cribbing beam, the combination of a vertical web, top and bottom flanges extending rearwardly from said vertical web, a plurality of apertures in one of said flanges spaced longitudinally thereof equi-distant from each end of the beam and on opposite sides of the vertical center of said beam, apertures in the other flange of said beam registering with said first named apertures and including an annular flange of less outside dimension than that of the apertures in the first-named apertured flange, said annular flange extending outwardly of the beam from its respective aperture, end flanges on said vertical web disposed between said top and bottom flanges and an aperture therein spaced from said vertical web of the beam.

9. In a cribbing structure, a filler member comprising a vertical web, rearwardly extending top and bottom flanges connected with the edges of said vertical web, apertures in said top and bottom flanges, the apertures in one flange having an annular flange extending outwardly from said vertical web, and vertically disposed reinforcing members connecting the top and bottom flanges adjacent opposite ends of the filler.

10. In a cribbing structure of the character described, a spacer member as a substitute for a stretcher member and comprising a vertical web, top and bottom flanges extending rearwardly

from said vertical web, the side edges of said web converging from one flange toward the other flange so that one of the horizontal edges of the vertical web and its associated flange is of less length than the opposite of said edges and its associated flange and a vertically disposed reinforcing member connecting said flanges intermediate the side edges of said vertical web.

11. In a cribbing structure, a header beam comprising a vertical web, a flange on one horizontal edge of said vertical web, and vertically spaced apertures in said vertical web adjacent opposite vertical edges thereof.

12. In a cribbing structure comprising stretcher and header members, a capping member supported by the uppermost stretcher member and comprising a vertical web, top and bottom flanges extending rearwardly from said web, vertically disposed reinforcing members connecting said top and bottom flanges adjacent the end portions thereof.

13. In a cribbing structure comprising stretcher and header members, a capping member supported by the uppermost stretcher member and comprising a vertical web, rearwardly extending top and bottom flanges, a depending flange adjacent the free edge of said top flange, and vertically disposed reinforcing members connecting said top and bottom flanges adjacent the ends thereof.

14. In a metal cribbing structure comprising superposed rows of self-supporting stretcher members, a stretcher member of substantially channel shape having a vertically disposed web extending longitudinally of the cribbing structure, a rearwardly disposed flange extending sub-

stantially the length of said web at the top thereof so as to provide support for the adjacent superposed stretcher member, a similarly disposed bottom flange on said web extending substantially the length thereof and terminating in a depending portion disposed outwardly of the vertical plane of the free edge of said top flange so as to overlap the top flange of the adjacent supporting stretcher member, and a plurality of vertically extending members disposed between said top and bottom flanges to maintain said flanges in fixed spaced relation and cooperating with similar members in adjacent stretcher members to provide rigidifying columns extending from top to bottom of the structure.

15. In a metal cribbing structure comprised of superposed rows of interlocking self-supporting stretcher members, a stretcher member of substantially channel shape having a vertically disposed web extending longitudinally of the cribbing structure and having its upper and lower portions inclined rearwardly of the major portion of the web and terminating in substantially horizontal flanges, the longitudinal free edge of the lower of said flanges terminating in a shorter depending flange, the said web having vertically extending and longitudinally spaced embossments connecting said flanges, the inner edges of the embossments lying in a vertical plane substantially at the attachment of said flanges to said web, and a plurality of vertically extending members disposed between and connected to said flanges.
